Primary Examiner—Ruth McInroy*Attorney, Agent, or Firm*—A. Burgess Lowe; Richardson B. Farley[57] **CLAIM**

The ornamental design of a hand held vacuum cleaner, as shown and described.

DESCRIPTION

FIG. 1 is a side view of our invention of a design for a hand held vacuum cleaner, the opposite side view being a mirror image thereof;

FIG. 2 is a top view thereof;

FIG. 3 is a bottom view thereof;

FIG. 4 is a bottom view similar to FIG. 3 but with the nozzle in an alternative position;

FIG. 5 is a front view of FIG. 1;

FIG. 6 is a front view similar to FIG. 5 but with the nozzle in an alternative position;

FIG. 7 is a rear view of FIG. 1;

FIG. 8 is a second embodiment thereof, the opposite side view being a mirror image thereof;

FIG. 9 is a top view thereof;

FIG. 10 is a bottom view thereof;

FIG. 11 is a front view thereof;

FIG. 12 is a front view similar to FIG. 11 with the nozzle in an alternative position;

FIG. 13 is a side view of the alternative nozzle position shown in FIG. 11; and,

FIG. 14 is a rear view of FIG. 8.

The crosshatch shading shown in FIGS. 1-4, 7-10 and 13-14 is understood to repeat throughout the indicated area.
